(57) **CLAIM**

The ornamental design for a rack for liquid solution generating and dispensing equipment as shown and described.

DESCRIPTION

FIG. 1 is a front perspective view of a rack for liquid solution generating and dispensing equipment according to my design;

FIG. 2 is a rear perspective view thereof;

FIG. 3 is a front elevation view thereof;

FIG. 4 is a rear elevation view thereof;

FIG. 5 is a right-hand side elevation view thereof;

FIG. 6 is a left-hand side elevation view thereof;

FIG. 7 is a top plan view thereof; and,

FIG. 8 is a bottom plan view thereof.

The broken lines in the drawings depict portions that form no part of the claimed design.
